(57) **CLAIM**

The ornamental design for an F connector, as shown and
described.

DESCRIPTION

FIG. 1 is a front perspective view showing my design for an F
connector;

FIG. 2 is a top view thereof, the claimed portion of which is a
mirror image to a bottom view;

FIG. 3 is a right side view thereof, the claimed portion of
which is a mirror image to a left side view;

FIG. 4 is a front view thereof on a larger scale; and,

FIG. 5 is a rear view thereof.

The broken line portion of the figure drawings is included to
show unclaimed subject matter only and forms no part of the
claimed design.

1 Claim, 5 Drawing Sheets
